FIRE-EXTINGUISHING LIQUID

Karl Dachlauer, Hofheim in Taunus, Germany, assignor, by mesne assignments, to General Aniline & Film Corporation, New York, N. Y., a corporation of Delaware

No Drawing. Application October 14, 1939, Serial No. 299,511. In Germany September 23, 1938

3 Claims. (Cl. 169—1)

The present invention relates to a fire-extinguishing liquid.

It is known to use chlorinated or brominated aliphatic hydrocarbons for fire-extinguishing purposes. In practice carbon tetrachloride, methyl bromide and ethylene bromide are chiefly used. Carbon tetrachloride, the most usual fire-extinguishing agent, however, has often proved to be insufficient for extinguishing a fire of readily combustible substances such as benzene. The methyl bromide is said to have a somewhat improved fire-extinguishing action, but owing to its low boiling point (+4.5° C.) it cannot readily be used alone. The main drawback of the methyl bromide, however, is its extraordinary poisonosity. According to another proposal methyl bromide is used together with brominated hydrocarbons of higher boiling point such as ethylene bromide (boiling point 131° C.). A certain improvement as to the use is attained thereby, but the poisonosity of the brominated hydrocarbons, especially of the methyl bromide, is not sufficiently diminished thereby.

Now I have found that liquid fire-extinguishing agents which contain at least one halogen derivative of aliphatic hydrocarbons of low molecular weight having the general formula

wherein m , n and x are at least one, and $m+n+x$ is equal to 4.

have a considerably better fire-extinguishing action than the agents consisting of compounds which contain in the molecule only bromine or chlorine alone. The new products are also superior to perhalogenated derivatives of the hydrocarbons, namely compounds of the character of paraffine in which all the hydrogen atoms are substituted by halogen atoms of one single kind or of different kinds. A further essential advantage of the new compounds for use as fire-extinguishing agents according to the present invention is that, in comparison with the substances hitherto used as fire-extinguishing agents, especially the brominated hydrocarbons, they are considerably less poisonous, even when coming in contact with flames, so that there is no risk in using them.

According to the invention for instance the following compounds are suitable for fire-extinguishing purposes: chlorobromomethane, dichlorobromomethane, 1-chloro-1,2-dibromoethane, dichlorodibromoethanes, 2,3-dichloro-1,2-dibromopropane and the like.

These compounds may be used per se or in admixture with each other or also together with other known liquid fire-extinguishing agents.

The comparative experiments described below prove the improved fire-extinguishing effect of hydrocarbons containing chlorine and bromine simultaneously:

(1) Several iron troughs of equal capacity and shape are filled with 10 liters of light benzine each and set on fire. After a burning for 2 minutes it is tried to extinguish the fire by spraying thereon different liquids, the fire-extinguishing effect of which is to be examined and compared, out of a hand fire-extinguisher of the kind generally applied for carbon tetrachloride. Such a hand fire-extinguisher consists of a pressure vessel wherein an ascending tube is inserted from above which nearly extends to the bottom of the vessel. The pressure vessel is partly filled with the extinguishing liquid and thereabove with compressed air which is fed by means of a pump or from a container. The ascending tube is connected with a spraying nozzle, a valve being intercalated. On opening this valve the fire-extinguishing liquid is pressed out of the nozzle by the action of the compressed air and is sprayed onto the burning matter. The hand fire-extinguishers used are all of the same type and are filled each with 1 liter of liquid. The following liquids are used: methylene chloride, chloroform, carbon tetrachloride, methyl bromide, chlorobromomethane, ethylene bromide, 1-chloro-1,2-dibromoethane, symmetrical dichlorodibromoethane and the mixture of equal parts of methyl bromide and ethylene bromide.

With the exception of chlorobromomethane, 1-chloro-1,2-dibromoethane and dichlorodibromoethane it is not possible with any of the said liquids, even not with the mixture of methyl bromide and ethylene bromide, to approximately stop the fire in the troughs filled with light benzine, though the entire content of the hand fire-extinguisher has been consumed. In the case of chlorobromomethane, however, half of the content and in the case of chlorodibromoethane and of dichlorodibromoethane $\frac{2}{3}$ of the content are sufficient for completely suffocating the fire in a trough.

(2) A sheet iron tank (length: 45 cm., breadth: 45 cm., height: 15 cm.) is placed in the center of a chamber of incombustible material (length: 2 m., breadth: 2 m., height: 2 m.) which is open from above and, for the purpose of a good admission of air to the burning matter, is mounted on feet. For each extinguishing experiment 4

liters of light benzine are filled into the tank and set on fire. After a burning for 4 minutes the liquids whose fire-extinguishing effect is to be examined are sprayed onto the burning matter, always from the same place through an opening in the chamber out of a hand fire-extinguisher of the kind described above (type Wintrich, hand fire-extinguisher A1). The hand fire-extinguisher always contains 1 liter of liquid which, by the action of the compressed air, is under a pressure of 8 atmospheres above atmospheric pressure. 48 to 51 seconds are necessary for completely vacating the hand fire-extinguisher.

With carbon tetrachloride (CCl_4 , boiling at $76.5^\circ C.$), dichlorodifluoromethane (CCl_2F_2 , boiling at $-29^\circ C.$), trichlorofluoromethane (CCl_3F , boiling at $+24^\circ C.$), trifluorotrifluorochloroethane ($CF_2Cl.CFCl_2$, boiling at $+47^\circ C.$), or difluorotrifluorochloroethane ($CF_2Cl.CHCl_2$, boiling at $+75^\circ C.$), it is not possible in any case to extinguish the fire though the entire content of the fire-extinguisher has been consumed.

With trichlorobromomethane (CCl_3Br , boiling at $104^\circ C.$) the fire is extinguished only after about 35 to 40 seconds.

With a mixture of about 80 per cent of chloro-

bromomethane and about 20 per cent of dichlorobromomethane (boiling at $70^\circ C.$ to $90^\circ C.$) the fire is extinguished in the course of about 7 to 10 seconds, the consumption of extinguishing liquid being about 200 cc. to 250 cc.

As shown by these experiments, the extinguishing liquids according to the present invention are also superior to perhalogenated derivatives of the hydrocarbons, even to such containing each 10 chlorine and bromine.

I claim:

1. The process of arresting a flame which comprises directing into the atmosphere in the neighborhood of the flame a chloro-, bromo- derivative of methane of the general formula

wherein m , n and x are at least one, and $m+n+x$ is equal to 4.

2. The process of arresting a flame which comprises directing into the atmosphere in the neighborhood of the flame chlorobromomethane.

3. The process of arresting a flame which comprises directing into the atmosphere in the neighborhood of the flame dichlorobromomethane.

KARL DACHLAUER.
